UNITED STATES PATENT OFFICE.

SAMUEL MARSH, OF CRYSTAL LAKE, ILLINOIS.

BUDGET SYSTEM.

Application filed August 31, 1923. Serial No. 660,270.

This invention relates to a record keeping sheet and particularly to a record keeping book in which a number of such sheets of graduated size are arranged together for cooperative use. One use of the invention is in connection with record keeping in which a number of totals of different classes of articles are visibly indicated in close association. Another use of the invention is in connection with account keeping and particularly in connection with account keeping in which a visible record of the sums expended is always available in which the record of the sum expended is subdivided into a plurality of individual categories. Other uses and objects of the invention will appear from time to time throughout the specification and the claims.

The invention is illustrated in one form in Figure 1 which shows an account keeping and budget record book.

Figure 2 illustrates a sheet from the book.

Like parts are designated by like characters throughout.

A is a cover for the book shown in Figure 1. B B are account or record keeping sheets of the smallest size used. Each sheet has indicated on its face a plurality of subdivided record keeping spaces, each space being marked to indicate a coin of a single denomination, thus, as shown in Figure 1, each sheet has spaces on it indicating cents, nickels, dimes, quarters, and half dollars. Along the side of the sheet is a column indicating dollars. As shown in the figures, space for thirty dollars is provided for in each column. This number might, of course, be varied. At the top of each sheet a title, indicating a certain class of expenditure, appears. These titles might be infinitely varied to provide for other classifications of expenditure or the spaces which they fill might be left blank so that the user might write in his own classification.

The arrangement of the various items appearing on each sheet might be almost infinitely varied. The dollar indicating portion might appear at the top or bottom or elsewhere, and the classification "Name" might correspondingly be moved about. My invention is not limited, therefore, to any particular arrangement of these various items. It is sufficient that there appear upon the sheets marking spaces for the various denominations of coins and a classification space, and that the space in which

coins of the highest denomination are designated and the classification space shall be visible at all times when the book is open as shown in Figure 1.

C C are sheets similar to sheets B B but larger. D D are sheets similar to the previously mentioned sheets, but still larger. E E are the largest sheets provided. Other sheets, of increasing size, might be used and my invention is therefore not limited to the use of four sizes of sheets. More or less than this number might be used. It is important, however, that the sheets shall be of such sizes and so arranged that when the book is open (as shown in Figure 1) that portion of each sheet indicating the classification of the expenditures marked upon it and that portion of the sheet indicating the coins of the highest denomination shall be visible and shall not be covered by any other sheet. Thus, when the book is open, it is possible at a glance to tell what the budget estimate of each class of expenditure is and what expenditure has been made to date. As shown in Figure 1, three sheets E E of identical size, are provided. This is in order to provide for the expenditure of a larger amount than that indicated on the first sheet in that classification. Where two identical sheets are provided in an association of this sort, the total of dollars, or whatever the coin of highest denomination be which is indicated on the sheet, runs successively from sheet to sheet, thus the total on the first sheet is from 1 to 30 and that on the second sheet is from 31 to 60.

As indicated in Figure 2, a loose leaf sheet is shown. The printing matter on these sheets is the same as that previously described and the manner of the arrangement of these sheets in whatever binder is used is such as to produce the same arrangement of sheets and visibility of items as shown in Figure 1. As shown in Figure 2, the sheet is perforated for use with a loose leaf binder.

The invention is not limited to any specific form of binding or associating together of the necessary sheets. They may be formed in a book bound together as in Figure 1, or some or all of them may be perforated and assembled together in a loose leaf binder which may be of any suitable type. Any number of sheets may be associated and any number of sheets of the same category may be associated together in a given binder, thus, for the sheet marked "Personal", not

one but many identical sheets may be associated together. The number of sheets used in any given binder is generally governed by the amount to be spent and by the time 5 for which a record is to be kept. In the form shown in Figure 1, a sufficient number of sheets is assembled to furnish a record for one month. For certain individuals a larger number of sheets might be necessary 10 for that period of time and it is within the contemplation of my invention that more sheets might be assembled either in a loose leaf binder or in a bound book, as shown in Figure 1, to cover a larger expenditure for 15 a month or to cover the expenditure for several months or for any desirable length of time.

The use and operation of the invention are as follows:

20 In whatever binder and in whatever quantity the sheets are assembled, their arrangement will be generally similar to that shown in Figure 1. While the book may be used merely to keep track of expenditures, it is 25 also adapted to be used in connection with expenditures designed to fall within a limited sum, that is, it may be used to keep track of expenditures which are made according to a prearranged budget, and its 30 use will be described in connection with a budget.

After the monthly allowance for each item has been determined in the budget, a cross is made in that dollar square on each 35 record sheet which represents the amount of the allowance. This should be done under each classification. Thereafter, as money is expended, checks will be made in some of the 40 ruled squares on the record keeping sheets, thus, if two dollars is spent under "Personal", the second dollar square on the dollar column under "Personal" will be checked. If the next expenditure is three dollars 45 under the same item, the fifth square in the dollar column will be checked, that is, the third square in addition to the two squares already checked. And thus the two expenditures, one of two dollars and the other of three dollars, are indicated with a total 50 expenditure of five dollars. This process is repeated whenever an expenditure is made.

Amounts less than one dollar under the same classification "Personal" are checked 55 on the same page from left to right, line after line, in their respective sections, and when a square containing a dollar mark is checked, it shows that a dollar's worth of that particular coin has been spent. Then 60 an additional dollar square in the dollar column is checked. Thus, if a half dollar is spent, a half dollar square is checked. If seventy-five cents is spent, the next half dollar square is checked, and the first quarter square is checked. The dollar mark in 65 the second half dollar square just checked

in the half dollar section warns the user to check another dollar in the dollar section on the margin of the sheet.

This dollar total is thus kept automatically and will show at a glance at any time 70 how expenditures are running under each of the several classifications. The method of checking expenses on each sheet is identical with that just described under the "Personal" sheet and by the use of all the 75 sheets the operator will have a constant visible indication of his total expenditures under each of the several classifications and he will also have a constant visible check indicating what proportion of his budget 80 estimated under each classification has been expended from day to day.

I claim:

1. In a record keeping book, a plurality of marked sheets, each having marked on it a plurality of separate subdivided sections, each of such subdivided sections marked to indicate a given unit of measurement, one of such sections adapted to indicate substantially the total of all of the 85 other sections, such sheets arranged together so that the portions indicating the totals of each of the sheets are simultaneously visible.

2. In a record keeping book, a plurality of marked sheets, each having marked on it a plurality of separate subdivided sections, each of such subdivided sections marked to indicate a given unit of measurement, one of such sections adapted to indicate substantially the total of all of the other sections, each sheet having on it also a classification indication, such sheets arranged together so that the portions indicating the totals and the classification of each of the sheets are simultaneously visible.

3. In a record keeping book, a plurality of marked sheets, each having marked on it a plurality of separate subdivided sections, each of such subdivided sections marked to indicate a given unit of measurement, one of such sections situated on the edge of the sheet and adapted to indicate substantially the total of all of the other sections, such sheets arranged together so that the portions indicating the totals of 110 each of the sheets are simultaneously visible.

4. In a record keeping book, a plurality of sheets, each having marked on it a plurality of separate subdivided sections, each of such subdivided sections marked to indicate a given unit of measurement, one of such sections situated on the edge of the sheet and adapted to indicate substantially the total of all of the other sections, each sheet having on it also a classification indication, such sheets arranged together so that the portions indicating the totals and the classification of each of the sheets are simultaneously visible.

5. In a record keeping book, a plurality 130

- of sheets, each having on it a plurality of subdivided sections, each of said sections marked to indicate a coin of a certain denomination, each sheet having on it a section marked to indicate the total of all the other subdivided sections, such sheets arranged together so that the portions indicating the totals of each of the sheets are simultaneously visible.
6. In a record keeping book, a plurality of sheets, each having marked on it a plurality of subdivided sections, each of said sections marked to indicate a coin of a certain denomination, each sheet having marked on it a section marked to indicate the total of all of the other subdivided sections, and each sheet provided with a designated space for a classification indication, such sheets arranged together so that the portions indicating the totals and the classification of each of the sheets are simultaneously visible.
7. In a record keeping book, a plurality of sheets of different sizes, each having on it a plurality of subdivided sections, each of said sections marked to indicate a coin of a certain denomination, each sheet having on it a section marked to indicate the total of all the other subdivided sections, such sheets arranged together so that the portions indicating the totals of each of the sheets are simultaneously visible.
8. In a record keeping book, a plurality of sheets, of different sizes, each having marked on it a plurality of subdivided sections, each of said sections marked to indicate a coin of a certain denomination, each sheet having marked on it a section marked to indicate the total of all of the other subdivided sections, and each sheet provided with a designated space for a classification indication, such sheets arranged together so that the portions indicating the totals and the classification of each of the sheets are simultaneously visible.
9. In a record keeping book, a plurality of sheets of graduated sizes, each having on it a plurality of subdivided sections, each of said sections marked to indicate a coin of a certain denomination, each sheet having on it a section marked to indicate the total of all the other subdivided sections, such sheets arranged together so that the portions indicating the totals of each of the sheets are simultaneously visible.
10. In a record keeping book, a plurality of sheets of graduated sizes, each having marked on it a plurality of subdivided sections, each of said sections marked to indicate a coin of a certain denomination, each sheet having marked on it a section marked to indicate the total of all of the other subdivided sections, and each sheet provided with a designated space for a classification indication, such sheets arranged together so that the portions indicating the totals and the classification of each of the sheets are simultaneously visible.
- the classification of each of the sheets are simultaneously visible.
11. In a record keeping book, a plurality of sheets of different sizes, each having marked on it a plurality of subdivided sections, each of said sections marked to indicate a coin of a certain denomination, each sheet having on its edge a column of numbered spaces marked to indicate the total in dollars of all of the other subdivided sections, each sheet provided at its top with designated space for a classification indication, such sheets arranged together so that the upper edge of each and the marked dollar section at the side of each are simultaneously visible.
12. In a record keeping book, a plurality of sheets of graduated sizes, each having, marked on it, a plurality of subdivided sections, each of said sections marked to indicate coins of a certain denomination, each sheet having on its edge a column of numbered spaces marked to indicate a coin of greater value than any other on the sheet, such sheets arranged together so that the marked section at the edges of the sheets are all simultaneously visible.
13. In a record-keeping book, a plurality of sheets, each sheet divided into two main parts, one of said parts having on it a plurality of subdivisions marked to indicate a coin the other of said parts having on it a plurality of separate groups of subdivisions being marked to indicate a coin of different denomination, in each of said groups of subdivisions marks to indicate when the number of coins checked in each is equal to one of the coins marked on the first mentioned part of said sheet, the coins being different from each other and from the coin on the first mentioned part of the sheet, such sheets arranged together so that the portions indicating the totals of all of the sheets are simultaneously visible.
14. A budget-keeping form comprising a sheet divided into two main parts one of said parts having on it a plurality of subdivisions marked to indicate a coin the other of said parts having on it a plurality of separate groups of subdivisions being marked to indicate a coin of different denomination, in each of said groups of subdivisions marks to indicate when the number of coins checked in each is equal to one of the coins marked on the first mentioned part of said sheet, the coins being different from each other and from the coin on the first mentioned part of the sheet.
15. A budget-keeping form comprising a sheet divided into two readily separable main parts one of said parts having on it a plurarality of sub-divisions marked to indicate a coin of a single denomination the other of said parts having on it a plurality of separate groups of sub-divisions each of

- said groups of subdivisions being marked to indicate a coin of a different denomination, in each of said groups of subdivisions marks to indicate when the number of coins checked in each is equal to one of the coins marked on the first mentioned part of said sheet, the coins being different from each other and from the coin on the first mentioned part of the sheet.
16. A budget-keeping form comprising a sheet divided into two parts one of said parts having on it a plurality of subdivisions each marked to indicate a coin the other of

said parts having a plurality of separate groups of subdivisions, each of said groups of subdivisions marked to indicate coins of a different and lesser denominations, in each of said last mentioned groups of subdivisions marks to indicate when the number of said lower coins check is equal to one dollar.

Signed at Chicago county of Cook and State of Illinois, this 23rd day of August 1923.

SAMUEL MARSH,
